New York

Application March 6, 1950, Serial No. 8,335

Term of patent 14 years

(Cl. D34—15)

To all whom it may concern:

Be it known that I, Frank Pettit, a citizen of the United States of America, and a resident of Union, in the county of Union and State of New Jersey, have invented a new, original, and ornamental Design for a Combined Car and Platform for Toy Railroad, of which the following is a specification, reference being had to the accompanying drawing forming a part thereof.

In this drawing:

Figure 1 is a perspective view of a combined car and platform for toy railroad showing my new design; and

Figure 2 is a top plan view thereof.

I claim:

The ornamental design for a combined car and platform for toy railroad, as shown.

FRANK PETTIT.
